UNITED STATES PATENT OFFICE.

ARBA G. BURROWS, OF JACKSON, ALABAMA.

WELL-BUCKET BOTTOM.

1,333,793.

Specification of Letters Patent. Patented Mar. 16, 1920.

Application filed December 6, 1919. Serial No. 342,967.

To all whom it may concern:

Be it known that I, ARBA G. BURROWS, a citizen of the United States, residing at Jackson, in the county of Clarke and State 5 of Alabama, have invented a new and useful Well-Bucket Bottom, of which the following is a specification.

This invention relates to new and useful improvements in well buckets, and more 10 particularly to the valve construction thereof.

The primary object of the invention is to provide a valve construction including a novel form of seat, which seat will absolutely insure the seating of the valve at all 15 times, regardless of the sediment contained in the fluid in which the bucket is operating.

With the foregoing and other objects in view which will appear as the description 20 proceeds, the invention resides in the combination and arrangements of parts and in the details of construction hereinafter described and claimed, it being understood that changes in the precise embodiment of 25 the invention herein disclosed, may be made within the scope of what is claimed, without departing from the spirit of the invention.

Referring to the drawing:—

Figure 1 illustrates a side elevational view 30 partly in section, of a well bucket bottom constructed in accordance with the present invention; and

Fig. 2 illustrates a sectional view taken on line 2—2 of Fig. 1.

Referring to the drawing in detail, the 35 reference character 5 designates the side walls of the well bucket to which my invention is applied, the bottom 6 however being secured within the side walls 5 in the usual 40 and well known manner.

This bottom 6 is provided with a central circular opening 7 which forms the filling opening of the bucket, the upper portion of 45 which is guarded by the cross bars 8 which have their respective ends seated in the cut out portions 9, formed in the upper edge of the bottom 6 adjacent the opening 7, the bars crossing each other intermediate the lengths thereof in a manner to prevent material such as gravel, or other foreign matter 50 from entering the bucket through the opening.

The valve seat, which forms an important

feature of the invention, includes a circular metallic plate 10, having a central opening 55 11 which is of a diameter slightly less than the diameter of the opening 7 of the bottom 6, and as shown the valve seat 10 is concavo-convex in formation, the convex surface thereof forming the upper surface of the 60 valve seat, while the concave surface thereof lies adjacent the upper surface of the bottom 6, adjacent the opening 7.

Disposed within the valve seat 10, adjacent the periphery thereof, are a plurality 65 of openings 12 which openings provide means for accommodating the screws 13 which secure the valve seat to the bottom 6 and absolutely prevent displacement of the valve seat with relation to the bottom 6. 70

Pivottally supported within the well bucket, and connected to the bottom 6 thereof, is the usual check valve 14 formed of suitable flexible material, and having a portion 15 of a size to substantially cover the 75 valve seat 10, the securing end thereof being fastened to the upper surface of the bottom 6 by means of the screws 16 passing through suitable openings in the plate 17, the points of the screw being embedded in the bottom 6. 80

The plate 17, is of a length equal to the width of the check valve 14, adjacent its securing end, which plate distributes the wear throughout the width of the check valve 14, which wear is directed thereto due 85 to the pivotal movement of the flexible material of which the same is formed, the plate thereby increasing the life of the valve proper.

From the foregoing it is obvious that due 90 to the concavo-convex construction of the valve seat 10, the valve proper contacts with only a portion of the valve seat 10, at a point adjacent the upper edge of the wall of the opening, portions of the check valve 14 adjacent the seat engaging portions thereof, lying in spaced relation with the valve seat so that foreign matter such as gravel, sand or the like which might collect on the valve seat 10, could not contact with the check 95 valve 14 to cause the same to remain unseated, after the bucket forming a part thereof, has been filled, which unseated valve ordinarily permits the fluid or water contained in the bucket 5 to drain therefrom. 100 105

It is believed that in view of the fore-

going specification, the detailed description as to the operation of the invention, step by step is unnecessary.

Having thus described the invention, what I claim is:—

A well bucket including a bottom, said bottom having an opening formed therein, said bottom having a cut out portion formed adjacent the upper end of the opening, guard bars having their ends positioned in the cut out portion, a valve seat including a metallic plate secured to the bottom directly over the opening, said metallic plate adapted to en-

gage the guard bars for securing the same within the bottom, and a check valve pivotally connected to the bottom and adapted to contact with the valve seat for controlling the passage of water through the bucket. 15

In testimony that I claim the foregoing as my own I have hereto affixed my signature in the presence of two witnesses. 20

ARBA G. BURROWS.
